SWISS BELL RINGING TOY

Joseph Green, Woodmere, N. Y.

Application April 5, 1957, Serial No. 45,600

Term of patent 3½ years

(Cl. D34—15)

Fig. 1 is a front perspective view of a Swiss bell ringing toy showing my new design; and

Fig. 2 is an end view thereof.

The back and bottom of the toy are flat and unornamented and form no part of the design.

I claim:

The ornamental design for a Swiss bell ringing toy, substantially as shown and described.
